LAMP HARP EXTENSION

Paul Chilo, Chicago, Ill.

Application January 18, 1950, Serial No. 139,169

3 Claims. (Cl. 240—148)

1

The invention relates generally to lamp structures, and more particularly to an extension member for lamp harps.

The invention has among its objects the production of an extension for use with electric lamp structures to provide an adjustment of a lamp shade with respect to the lamp harp and base, which extension is attractive in appearance, simple in construction, and inexpensive to manufacture.

Another object of the invention is the production of such an extension by means of which adjustments over a relatively wide range may be accomplished, at the same time providing adequate support for the lamp shade in any position of adjustment.

A further object of the invention is the production of such an extension member which is designed for rigid connection with a like member whereby a plurality of such members may be employed as a composite extension.

The invention is of particular use in facilitating the use of a large replacement lamp shade on a particular lamp base which would otherwise be small for such larger shade.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters represent like or corresponding parts:

Fig. 1 is a perspective view of a harp extension embodying the present invention;

Fig. 2 is a vertical, sectional view of such an extension, with a similar extension connected thereto, portions of the latter being broken away;

Fig. 3 is a sectional view taken approximately on the line 3—3 of Fig. 2;

Fig. 4 illustrates a lamp base and shade before the application of an extension thereto;

Fig. 5 is a figure similar to Fig. 4 illustrating the use of a single extension; and

Fig. 6 is a figure similar to Fig. 4 illustrating the use of a plurality of extension members.

Referring to the drawings, and more particularly Figs. 1 to 3, 1 indicates an extension member comprising a hollow body 2 formed from relatively light gauge sheet material, or the like, formed by stamping, spinning, drawing, or other suitable operation, into a cup-shaped structure having a cylindrical side wall 3, and a bottom wall, indicated generally by the numeral 4. As

2

illustrated in Figs. 2 and 3, the bottom 4 is provided with a generally cylindrical recess 5 axially aligned with the axis of the body 2, with the bottom wall 6 of the recess being provided with an internally threaded bore 7. The open end 8 of the body 2 is closed by a cap member 9 rigidly secured to the body 2, and in the embodiment of the invention illustrated, the upper peripheral portion of the body adjacent the open end 8 is flared peripherally outwardly to form a slight bead 11 over which the cap member 9 is crimped or spun, as indicated at 12. The central portion 13 of the cap member 9 is offset outwardly with respect to the peripheral portions of the latter, as indicated at 14, and formed in the central portion 13 is a bore 15, in which is positioned the lower end 16 of a stud 17, the latter having an externally threaded portion 18 adjacent its upper end, with the lower portion 16 and threaded portion 18 being separated by an annular flange 19 bearing against the adjacent surface of the central portion 13 of the cap. The bore 15 and portion 16 of the stud 17 are of a relative size to achieve a press fit between the portion 16 and the side walls of the bore 15, thereby rigidly securing the stud 17 to the cap 9, the axis of the stud 17 being aligned with the axis of the bore 7.

Lamp shades such as the shade S diagrammatically illustrated in Fig. 4 are normally connected to a lamp base B by means of a harp H, the top portion of which carries a suitable fitting, indicated generally by the letter F. As is well known in the art, such fittings normally are provided with a stud corresponding to the stud 17 adapted to be encircled by a portion of the lamp frame assembly, which is held in position by an ornamental knob A, or the like, threaded on the stud carried by such fitting. A standard sized stud is normally employed in such fittings, and the stud 17 is constructed of the same size and with the same number of threads as the stud on the usual lamp harp fitting. Likewise, the threaded bore 7 in the bottom of the extension is of a size and provided with like internal threads to receive the standard stud. Thus, as illustrated in Fig. 2, the stud 17 of a similar extension member 1' may be readily screwed into the threaded bore 7 of the extension 1.

Oftentimes it is desired to replace the shade of a lamp with another shade which is larger than the original shade designed for use with the particular lamp base; as a result of which the larger lamp shade is not positioned properly with respect to the lamp base, and consequently does not impart a pleasing appearance or hides a portion of the lamp base, an example of such

condition being illustrated in Fig. 4, wherein the shade S extends down and partially hides the upper portion of the lamp base. The correct position of the lamp shade shown in Fig. 4 is illustrated in Fig. 5, in which the shade has been elevated with respect to the base to reveal the top portion of the latter. Such elevation of the lamp shade is readily accomplished by adding an extension member, such as illustrated in Fig. 1, screwing the extension down on the stud carried by the lamp harp, following which the supporting structure of the lamp shade is placed on the stud 17, and the original knob A engaged with the stud.

If a still larger or higher shade is to be utilized, as for example, the shade S' in Fig. 6, proper positioning of the shade with respect to the lamp base may be accomplished by using a plurality of extension members, the use of three such members being illustrated in Fig. 6, with the respective members 1 being secured to one another, as illustrated in Fig. 2, the lowermost extension member being engaged with the stud on the fitting F of the harp, and the knob A being engaged with the stud 17 of the uppermost extension member, with the latter directly supporting the shade S'.

It will be noted that the recess 5 in the bottom of each member is of a size to receive the annular flange 19 of a like member or a similar flange carried by the stud on the harp fitting, with the annular-shaped surface of the bottom 4 engaging the surface of the central portion 13 of the member positioned therebelow. Likewise, the extension member mounted on the fitting F of the lamp will similarly bear on the adjacent surface of the fitting as the extension member is drawn down tightly on the fitting F, with the annular shape of the bottom surface of the extension eliminating any tendency of a rocking movement therebetween. Thus, as illustrated in Fig. 2, the fitting and extension member, or extension members, are securely connected to form, in effect, a composite structure that is very rigid. The number of extension members employed in any given case will, of course, depend upon the desired elevation required in any particular application.

It will be noted from the above description that the extension member may be readily and inexpensively manufactured by a relatively simple process to produce a very efficient and durable device which is pleasing in appearance, and harmonizes with the usual lamp harp structures. Likewise, that I have provided an extension member which is so constructed that a series of such members may be employed as a single rigid unit.

Having thus described my invention, it is obvious that various immaterial modifications may be made in the same without departing from the spirit of my invention; hence, I do not wish to be understood as limiting myself to the exact form, construction, arrangement, and combination of parts herein shown and described or uses mentioned.

What I claim as new and desire to secure by Letters Patent is:

1. An extension for use with a lamp harp having a shade mounting stud extending therefrom comprising a cylindrical body member, the bottom end wall thereof being provided with an axially aligned recess therein, the bottom wall of said recess having an axially aligned, internally threaded bore therein of a size to receive a lamp harp stud, the central portion of the opposite end of said body member being offset outwardly and

having an axial bore therein, a stud, and an annular flange formed on said stud intermediate its ends, the portion of said stud at one side of said flange being provided with external threads, said threaded portion being substantially the same diameter and having the same number of threads per inch as said threaded bore, the opposite end portion of said stud being positioned in the bore in said opposite end and engaging the side walls thereof in a press fit whereby the stud and body member are rigidly secured together, with the flange on said stud being smaller in diameter than that of the recess in said bottom wall of the body member, and less in thickness than the depth of such recess, said flange being seated on the body member.

2. An extension for use with a lamp harp having a shade mounting stud extending therefrom comprising a hollow body member open at one end and having cylindrical side walls and bottom end wall, the latter being provided with an axially aligned recess therein, the bottom wall of said recess having an axially aligned, internally threaded bore therein of a size to receive a lamp harp stud, a cap secured to and closing the open end of said body member, said cap member having an axial bore therein, a stud, and an annular flange formed on said stud intermediate its ends, the portion of said stud at one side of said flange being provided with external threads, said threaded portion being substantially the same diameter and having the same number of threads per inch as said threaded bore, the opposite end portion of said stud being rigidly secured to said cap, with the flange on said stud being smaller in diameter than that of the recess in said bottom wall of the body member, and less in thickness than the depth of such recess, said flange being seated on the adjacent external surface of said cap.

3. An extension for use with a lamp harp having a shade mounting stud extending therefrom comprising a hollow body member open at one end and having cylindrical side walls and bottom end wall, the latter being provided with an axially aligned recess therein, the bottom wall of said recess having an axially aligned, internally threaded bore therein of a size to receive a lamp harp stud, a cap closing the open end of said body member, the side wall of the latter at said open end being provided with an external, peripheral bead, said cap member having a peripheral flange thereon engaged with said bead to rigidly connect the body member and cap to one another, the central portion of said cap member being offset outwardly and having an axial bore therein, a stud, and an annular flange formed on said stud intermediate its ends, the portion of said stud at one side of said flange being provided with external threads, said threaded portion being substantially the same diameter and having the same number of threads per inch as said threaded bore, the opposite end portion of said stud being positioned in the bore in said cap and engaging the side walls thereof in a press fit whereby the stud and cap are rigidly secured together, with the flange on said stud being smaller in diameter than that of the recess in said bottom wall of the body member, and less in thickness than the depth of such recess, said flange being seated on the adjacent external surface of said cap.

PAUL CHILO.
